G. M. KERRIHARD

OIL BURNER

Filed Feb. 24, 1922

Patented Mar. 20, 1923.

1,449,007

UNITED STATES PATENT OFFICE.

GEORGE MILLER KERRIHARD, OF RED OAK, IOWA, ASSIGNOR TO THE KERRIHARD COMPANY, OF RED OAK, IOWA, A CORPORATION OF IOWA.

OIL BURNER.

Application filed February 24, 1922. Serial No. 538,831.

To all whom it may concern:

Be it known that I, GEORGE M. KERRIHARD, a citizen of the United States, and a resident of Red Oak, in the county of Montgomery and State of Iowa, have invented 5 certain new and useful Improvements in Oil Burners, of which the following is a specification.

My invention relates to improvements in 10 oil burners, and it consists in the combinations, constructions and arrangements herein described and claimed.

An object of my invention is to provide 15 an oil burner of simplified construction which is adapted for use in furnaces of various known types of construction in which coal has heretofore been used as a fuel, without any extensive changes, if any, in the usual construction of the furnaces being 20 required.

A further object of my invention is to provide a burner of the character described with which the heavier and cheaper grades of oil, as well as the lighter grades, may be 25 used as a fuel with satisfactory results and safety.

Other objects and advantages will appear in the following specification and the novel features of the invention will be particularly 30 outlined in the appended claims.

My invention is illustrated in the accompanying drawings, forming a part of this application, in which:

Fig. 1 is a top plan view of the burner 35 with an upper section thereof removed.

Fig. 2 is a section through the burner along the line 2—2 of Fig. 1, and showing the burner in position on the grate of a furnace,

Fig. 3 is a section along the line 3—3 of Fig. 1, and

Fig. 4 is a side elevation of a burner nozzle cover embodied in the invention.

In carrying out my invention, I provide 45 a body portion 1 which comprises a central portion 2, an outer ring portion 3 and integral lug portions 4 merging the central portion 2 and the outer ring 3 one into the other and spacing the outer ring from the central 50 portion. The central portion 2 has substantially the shape of a disk formed with a continuous upstanding flange 5 around its outer edge and with an upstanding central burner nozzle or tip 6. The body portion prefer- 55 ably is made by casting in a single piece

and the outer ring portion 3 is spaced from the central portion 2 by the lugs 4 in such a manner as to be concentric therewith, whereby an annular passage 7 is provided between the central portion 2 and the outer 60 ring portion 3.

The central portion 2 is formed with the portion thereof extending between the flange 5 and the burner tip 6 depressed as shown to define the bottom of a reservoir 8 which 65 has a utility that will be hereinafter set forth. The burner tip 6 projects above the level of the flange 5 and is surrounded at the base thereof by stepped shoulders 9 and 10 respectively, formed at different levels. 70 The outer wall of the burner tip 6 tapers uniformly from the shoulder 9 toward the upper end thereof. A bore 11 extends axially of the burner tip 6 and is merged at the lower end into a threaded counterbore 75 12 opening through the lower face of the central portion 2. The discharge orifice of the bore 11 at the upper end of the tip is defined by intersecting slits 13 and 14 through the walls of the tip at the extreme 80 upper end of the latter.

The central portion 2 is formed with a radially extending enlargement or boss 15 provided with a bore 16 communicating with the reservoir 8 adjacent to the upper 85 end of the latter. The bore 16 is enlarged and threaded adjacent to the end thereof opening through the lower face of the central portion 2, as at 17, for connection with a drain pipe 18.

A ring-shaped baffle member 19, also formed of a metal casting, has the shape illustrated to advantage in Fig. 2, being substantially U-shaped in radial section. The baffle member 19 rests upon the upper 95 end of the outer ring portion 3 and is maintained thereon by a cylindrical casing member 20 which encompasses the outer ring portion 3 and projects above the latter. The baffle member 19 is thus supported in position to overhang the flange 5 and with the constricted or inner end thereof depending within the reservoir 8 below the level of the flange 5.

A cover for the burner tip comprises a 105 cylindrical member 21 threadedly engaged at its upper end by a cap 22 and being open at its lower end. The tubular member 21 is adapted to rest on the shoulder 10, whereby the inner wall thereof will be spaced from 110

the outer wall of the burner tip 6. Notches 23 are provided in the lower end of the tubular member 6. Obviously, the cylindrical member 21 and the cap 22 may be formed 5 integrally with each other, as by casting, and provided with a ring (not shown) or the like, whereby the burner nozzle cover may be lifted from the body for cleaning during the operation of the device, which will 10 be hereinafter described, without departing from the spirit and scope of the invention.

From the foregoing description of the various parts of the device, the operation thereof may be readily understood. The 15 burner may be installed within a furnace which was designed to be a coal burning furnace, without any extensive changes or alterations in the construction of the furnace being required. The burner is placed 20 in the firebox of the furnace in superimposed position on the grate, care being taken that the body portion is so disposed with respect to the grate that air is permitted to circulate freely through the grate into 25 the annular passage 7. It is important that the burner be truly horizontal and to this end, a plurality of jack screws 24 depend from threaded openings 25 through the lugs 4 and provide adjustable supports which 30 rest upon the grate bars 26. It will be understood that the jack screws can be manipulated until the burner is level. A feed tube 27 is extended between the grate bars and attached to the threaded counterbore 12. It 35 is to be understood that the feed tube 27 extends to a source of fuel supply (not shown) and that a fuel, such as a suitable oil, will be forced along the tube 27 into the burner tip 6 under pressure. It will be understood also that suitable means, none being shown, such as a needle valve, are provided in the feed tube 27 for controlling 40 the flow of a liquid fuel therethrough.

When the burner has been positioned 45 upon the grate bars 26, a suitable refractory material such as clay, is packed around the casing 29, as indicated at 28, to deflect all ascending currents of air upwardly through the grate bars 26 into the annular passage 7. Such air currents will be deflected downwardly by the baffle member 19 upon the 50 surface of the oil or like fuel which has been fed through the notches 23 to the reservoir 8, which serves as a flame basin.

On account of the restricted nature of the 55 passage between the cover and the burner nozzle, the oil passes through the notches 23 into the basin 8 at a desired rate of flow. It is to be observed at this point that the inner 60 wall of the cap 22 is formed to provide a conoidal chamber 29, the axis of which is in vertical alignment with the axis of the burner nozzle and that the notches 23 are spaced apart, whereby the oil flowing into 65 the flame basin will be fed to all parts of

the latter uniformly. When the fuel passing into the basin has been ignited, as by placing a lighted paper about the lower end of the burner nozzle, the downwardly directed air currents impinging against the 70 oil in the basin will promote combustion and such fuel will be practically completely consumed, thereby effecting a great economy in the generation of a desired amount of heat.

In the event that oil should be forced 75 from the burner nozzle into the basin 8 without being ignited, or in excess to the amount consumed, such oil will collect in the basin 8 and when the level of the passage 16 has been reached, will flow through the latter 80 and through the drain pipe 18, thereby apprising an operator that the burner is not functioning in a desired manner. If desired, a suitable safety shut-off valve of any known type of construction, none being 85 shown, may be operatively connected with the drain pipe 18 and the feed pipe 27 and arranged to be operated automatically to cut off the flow of fuel through the feed pipe 27 when such fluid fuel is passing from the 90 reservoir 8 through the drain pipe 18.

I claim:—

1. A burner comprising a body portion consisting of a central portion, an outer ring portion, and lug portions connecting 95 the central portion and the ring portion together in such a manner as to space the outer ring portion from the central portion, said central portion being provided with a vertically extending fuel nozzle, and means 100 superimposed upon said outer ring portion and overhanging the central portion for deflecting air currents passing between said central portion and said outer ring portion toward the portion of the body surrounding 105 the base of said nozzle.

2. A burner comprising a body portion having a central portion of substantially circular conformation, said central portion having an upstanding marginal flange, and 110 a vertical fuel nozzle projecting from the center thereof above the level of the flange, an outer ring member of greater diameter than the central portion, and lugs joining the central portion to the outer ring portion 115 and maintaining the latter in spaced concentric relation to the former, and means for directing currents of air passing between said central portion and said outer ring portion downwardly toward the surface of the body surrounding the base of the fuel nozzle.

3. A burner comprising a body made of a single casting, said body consisting of a central portion of circular conformation, an 125 outer ring portion of greater diameter than the central portion, and radially extending lugs integral with both the central portion and the outer ring portion and merging one into the other, whereby said central portion 130

- and said outer ring portion are located in spaced concentric relation and an annular passage is defined therebetween, said central portion having a continuous upstanding marginal flange and a vertical fuel nozzle projecting from the center thereof above the level of the flange, thereby defining a reservoir in the upper face of the central portion, said flange having a radial enlargement provided with a bore communicating with the reservoir adjacent to its upper end and opening through the lower face of the central portion.
4. A burner comprising a body made of a single casting, said body consisting of a central portion of circular conformation, an outer ring portion of greater diameter than the central portion, and radially extending lugs integral with both the central portion and the outer ring portion and merging one into the other, whereby said central portion and said outer ring portion are located in spaced concentric relation and an annular passage is defined therebetween, said central portion having a continuous upstanding marginal flange and a vertical fuel nozzle projecting from the center thereof above the level of the flange, thereby defining a reservoir in the upper face of the central portion, said flange having a radial enlargement provided with a bore communicating with the reservoir adjacent to its upper end and opening through the lower face of the central portion, a baffle member resting upon said outer ring portion and overhanging said central portion to depend below the level of said flange for diverting air currents downwardly into said reservoir, and means encompassing said burner tip and spaced therefrom for controlling the flow of the fuel from said nozzle into said reservoir.
5. A burner comprising a body made of a single casting, said body consisting of a central portion of circular conformation, an outer ring portion of greater diameter than the central portion, radially extending lugs integral with both the central portion and the outer ring portion and merging one into the other whereby said central portion and said outer ring portion are located in spaced concentric relation and an annular passage is defined therebetween, said central portion having a continuous upstanding marginal flange and a vertical fuel nozzle projecting from the center thereof above the level of the flange, thereby defining a reservoir in the upper face of the central portion, said flange having a radial enlargement provided with a bore communicating with the reservoir adjacent to its upper end and opening through the lower face of the central portion, and adjustable supporting members depending from said body portion for positioning said body portion horizontal when superimposed upon a fixed support.
6. A burner comprising a body made of a single casting, said body consisting of a central portion of circular conformation, an outer ring portion of greater diameter than the central portion, radially extending lugs integral with both the central portion and the outer ring portion and merging one into the other whereby said central portion and said outer ring portion are located in spaced concentric relation and an annular passage is defined therebetween, said central portion having a continuous upstanding marginal flange and a vertical fuel nozzle projecting from the center thereof above the level of the flange, thereby defining a reservoir in the upper face of the central portion, said flange having a radial enlargement provided with a bore communicating with the reservoir adjacent to its upper end and opening through the lower face of the central portion, and a baffle member resting upon said outer ring portion and overhanging said central portion to depend below the level of said flange for diverting air currents downwardly into said reservoir, and a cover encompassing said tip and resting upon the upper face of the central portion, said cover being closed at its upper end and being provided with notches in its lower end through which the fuel may pass into said reservoir.
7. A burner comprising a body made of a single casting, said body consisting of a central portion of circular conformation, an outer ring portion of greater diameter than the central portion, radially extending lugs integral with both the central portion and the outer ring portion and merging one into the other whereby said central portion and said outer ring portion are located in spaced concentric relation and an annular passage is defined therebetween, said central portion having a continuous upstanding marginal flange and a vertical fuel nozzle projecting from the center thereof above the level of the flange, thereby defining a reservoir in the upper face of the central portion, said flange having a radial enlargement provided with a bore communicating with the reservoir adjacent to its upper end and opening through the lower face of the central portion, a baffle member resting upon said outer ring portion and overhanging said central portion to depend below the level of said flange for diverting air currents downwardly into said reservoir, and a cover encompassing said tip and resting upon the upper face of the central portion, said cover being closed at its upper end and being provided with notches in its lower end through which the fuel may pass into said reservoir.
8. A burner comprising a body having a central portion of circular conformation, an outer ring portion, and radial portions connecting the central portion and the outer ring portion and maintaining these portions in spaced concentric relation, said central portion being provided with a fuel nozzle, upstanding from the center thereof and with a continuous upstanding marginal flange, said fuel nozzle having an axial bore formed

at its lower end for connection with a fuel supply pipe and being provided at its upper end with a discharge orifice defined by intersecting slits through the walls of the 5 burner at the upper end thereof, the outer wall of said burner tapering at the upper end thereof, a cover for said burner tip, said cover being provided with notches at its lower end, and a ring-shaped baffle member 10 resting upon said outer ring portion and having a portion thereof depending below the level of said flange within the space defined by said flange.

9. A burner comprising a base having a 15 central portion provided with a central ver-

tically disposed fuel nozzle upstanding therefrom and being formed to provide a flame basin on the upper face of the central portion in encircling relation to the base of the nozzle, and means associated with the 20 base in concentric spaced relation to the central portion for deflecting air currents passing upwardly around the edge of the base inwardly and downwardly toward the base of the nozzle, said central portion being 25 provided with a drainage bore communicating therewith above the level of the bottom of the flame basin.

GEORGE MILLER KERRIHARD.
